US00D384033S

United States Patent [19]

Takeda et al.

[11] Patent Number: Des. 384,033

[45] Date of Patent: **Sep. 23, 1997

[54] **ENGINE-DRIVEN ELECTRIC GENERATOR FOR WELDING**

[75] Inventors: **Masanobu Takeda; Yasumasa Mizuno; Shunichi Tetsui**, all of Kawagoe; **Hirotaka Yamamoto**, Tokyo, all of Japan

[73] Assignee: **Denyo Kabushiki Kaisha**, Tokyo, Japan

[**] Term: 14 Years

[21] Appl. No.: 52,658

[22] Filed: Apr. 2, 1996

[51] LOC (6) Cl. 13-02

[52] U.S. Cl. D13/114

[58] Field of Search D13/114; 315/304; 322/4

[57] **CLAIM**

The ornamental design for an engine-driven electric generator for welding, as shown and described.

DESCRIPTION

FIG. 1 is a front view of the engine-driven electric generator for welding embodying our new design;

FIG. 2 is a rear view thereof;

FIG. 3 is a right side view thereof, the left side view being a mirror image thereof;

FIG. 4 is a top plan view thereof; and,

FIG. 5 is a bottom view thereof.
